ELECTRICAL SOCKET

Harry W. Wellington, Chicago, Ill.

Application December 6, 1946, Serial No. 714,444

1 Claim. (Cl. 200—51.02)

1 This invention relates to an improved electrical socket. More specifically it relates to an improved electrical socket in which its internal mechanism if defective can be readily replaced without possible injury to a person—or even shutting off as a safety measure the source of electrical energy.

It therefore is an object of this invention to provide an electrical socket that can be readily repaired.

It is a further object of this invention to provide an electrical socket that can be safely repaired while the live circuit is alive.

A still further object of my invention is to provide an efficient electrical socket with an internal switch mechanism that can be readily and economically made on present type of manufacturing equipment.

An additional object of my invention is to provide a switch mechanism that in combination with my improved socket can be readily inserted into a live circuit with absolute safety and freedom of bodily harm that is inherently characteristic when such repairs are attempted with conventional electrically alive sockets.

These and other objects, adaptations, variations, modifications and extensions of my invention can be readily improvised and constructed by a person skilled in this art, and which particularly in view of the clear and lucid description given hereinbelow, should be considered as being within the orbit and confines of the concepts of the fundamental principles of my invention. Nevertheless, for purposes of this disclosure, a clear descriptive illustration of one or more of several possible species and variations will be given for purely exemplary purposes. Under no conditions shall it be construed directly or by implication as a limitation of my invention which is defined and limited by the appended claim given hereinbelow.

To further illustrate and clearly show the fundamental concepts underlying my invention, the attached drawings forming a part of this disclosure, show the application of my invention as related to an electrical socket.

In Figure 1, there is shown the external appearance of my improved socket which to all outward appearance is quite similar to the standard type.

Figure 2 shows a partially exploded view of the essential components of my improved socket and in combination therewith the switch mechanism.

Figure 3 is a vertical section taken thru the socket, but showing therein and in combination

2 therewith, my improved switch mechanism. It also shows a spring coil that assists in expelling the socket mechanism and simultaneously cutting contact thereby with the live circuit contacting points.

Figure 4 is an end view of the replaceable switch unit.

Figure 5 is a modification of a retaining means to keep the replaceable socket in place when it is used in an inverted position as in case of table lamps, etc.

Figure 6 is a view of another means that can be used to hold the replaceable socket in position against the female part of the outer shell.

15 Figure 7 is a partial sectional view of the interior of the upper part of the socket casing and the switch mechanism contacting portion in which are two contacting elements of different lengths.

20 In practising my invention, I take the electrical leads 10 and allow them to enter the socket 20 thru port 12 and fasten them to the contact screws 14. The latter are threaded into proper inserts 16 which are molded integrally or otherwise

25 formed within the casing of the socket 20. The socket 20 consists of two portions, an upper portion 18 and a lower portion 28. The upper portion 18 of the socket has a series of threads 22 at the lower part thereof which are engaged

30 within a complementary series of threads 24 found within the upper top of the inner side of the chamber 26. The top portion 18 at one side thereof has a customary recess 30 to provide an outlet for the pull chain 32 or other mechanism provided to turn on and off the electrical power.

The switch mechanism 32 is of the conventional type but in combination therewith I place therein the elements that are essential to my invention. In the improved switch mechanism I

40 provide one or more spring like members 34 substantially formed as shown in Figures 2, 3, 4 and 7. In the exploded view (Figure 2) as well as the modification in Figure 7, the spring like members are in a relaxed position, while in Figure 3 they

45 are under a compression. One end of the spring like member 34 is permanently fastened to the switch mechanism 32 by screws 36 while the other end is free, but having its broad flat surface substantially curved arcuately in an off horizontal plane so that an intimate spring contact can be maintained with contact screws 14.

50 It is obvious that the spring like members 34 can also be fastened directly to the casing 18 of the socket 20 by means of screws 14 or other

convenient means, and have the same effect as if they were fastened to the switch mechanism.

It will be observed that the spring like members 34 are the liaison parts between the contact screws 14 and the contact points 36 on the switch mechanism. Once this relationship is established then the current will flow uninterrupted thru the entire socket to the appliance. Since this action is well known there will be little need to discuss the electrical circuit.

It is apparent that the spring like connecting members 34 will have a tendency to separate and eject the switch mechanism 32 from the upper portion 18 of the socket. This action occurs when the lower part 28 of the socket 20 is disengaged from external threads 22 of the upper part 18. When this is done, the springs 34 force outwardly or upwardly the switch mechanism 32 and it can be readily removed from the socket 20. If the switch mechanism is defective, it can be readily replaced by another, and the socket is again functioning.

If the socket is used in an inverted position, that is the open end is facing downwardly or where it can be readily turned over, then the switch mechanism 32 can be readily removed since it will fall by action of gravity. Thus it can be replaced with a new switch mechanism even while the electrical current is on. However, if the socket cannot be readily removed by gravity then it is desirable to use other modifications to eject the switch mechanism. If the current is on, then the switch is alive and obviously it cannot be picked off for the fear of injury to the person. In this case, I prefer to place two similar shaped spring like members 34, except that one of these is sufficiently longer 34a so that when the lower portion 28 of the socket is unscrewed, the switch mechanism 32 will be forced upwardly by the spring elements 34. Since one of these elements 34a is longer than the other, it is then obvious that the electrical circuit thru lines 10 will be broken, for the shorter spring element 34 will not be in contact with the contact screws 14. If it is desired to mount the said spring like members of unequal length on the terminal screws 14, the same action will occur. The spring of the longer length will carry the switch mechanism 32 higher and thus break the circuit in the switch mechanism 32.

Though it is possible to fasten the spring like members 34 and 34a to the socket casing upper part lead screws 14, I prefer to use them in the position shown in Figure 7. Spring members made of brass, copper or other electrically conducting materials in due course of time, lose their elasticity and temper, and ordinarily are the source of trouble.

There are obviously other means of accomplishing the same object once a person skilled in this art is given an opportunity to understand the principles involved and the fundamental concepts underlying my invention. As another illustration of the principles but not a limitation thereof, I may if I desire, in place of said unequal length spring like members 34 and

34a, use equal lengths and place between the socket upper portion roof and the top of switch mechanism 32 a spring 38 which will act the same way and will be capable of ejecting the switch mechanism away from contact with the line leads 10. This spring 38 (shown as another modification in Figure 3) is made of quartz rod, glass, plastic or some other non-conducting material and which is capable of having spring characteristics.

Another means that can be utilized not only with the unequal arm spring elements principle, but also independently thereof is a spring means 40, which retains the switch mechanism 32 when the lower portion 28 of socket 20 is unscrewed. As it is unscrewed, the spring bayonet clip 40 will hold the switch mechanism threads 48 and remove it simultaneously. Likewise, another clip 42 having a lip 44 and serrations 46 can be inserted into the junction between the socket halves and act in the same way. The serrations 46 engage the bulb threads 48 of the switch mechanism and thus the switch is removed when the lower half of the socket is removed.

Quite obviously, there are a number of variations that one skilled in the art can be expected to devise in light of this disclosure, and it therefore is not my intention to be limited thereby except in accordance with the claim appended hereinbelow which defines the ambit and scope of the fundamental concepts underlying my invention.

I claim:

An improved electrical socket comprising an outer casing, the said casing comprising at least two parts, a means thereon to hold said parts in closed relationship, a means in one of said parts to fasten thereto electrical wire leads, a switch means within the said casing, expulsion type spring means in electrically contacting juxtaposition with the said wire leads and said switch, one of said spring means being longer than others, whereby the electrical circuit in the switch mechanism is broken by the unequal expansion of the longer spring when the casing parts are disjointed.

HARRY W. WELLINGTON.
